WIRE BELT AND CONNECTER THEREFOR

Raymond J. Guba, Haddon Heights, N. J., assignor to Audubon Wire Cloth Company, Audubon, N. J., a corporation of New Jersey

Application August 27, 1930. Serial No. 478,206

6 Claims. (Cl. 198—193)

My invention relates to that type of flexible belt for conveyers and/or the like which is made of woven wire fabric consisting of individually wound or twisted strands of wire interlaced together and lying at right angles to or crosswise of the longitudinal axis of the belt.

The principal object of my invention is to provide a belt of this character with means for maintaining its width substantially the same throughout its length.

A further object of my invention is to provide belts of this character made up of sets or series of sections or panels of wire fabric formed of helically twisted strands or members of wire in which such helical wire members of the respective sections or panels are reversely arranged relatively to each other; that is to say, in such manner that the convolutions of the helically twisted wires which provide upper and under (or lower) ribs of one section extend in a substantially opposite direction with respect to the convolutions which provide upper and under (or lower) ribs of the helically twisted wires of other and adjacent sections, with connector bars disposed between the respective sections; such connector bars being so secured to such helically wound or twisted wires as to prevent movement of the same lengthwise thereof or laterally with respect to the longitudinal axis of the belt and thereby prevent narrowing of the latter.

A further object of my invention is to permanently fasten to opposite sides or edges of said connector bars individual helical wire strands which may have their convolutions providing the upper and under (or lower) ribs lying in the same or opposite directions, and to which helical wire strands so connected other helical strands of wire may be interlaced or twisted in the formation of a belt or belt section.

A still further object of my invention is to provide connector bars for said belt sections or panels to which the end wires of such sections may be welded.

A still further object of my invention is to provide connector bars as articles of manufacture, the same having permanently associated therewith helically twisted strands of wire arranged with their convolutions forming the upper and under (or lower) ribs in the same or different directions at opposite sides of such connector bars, and to which other helically twisted wires may be interlaced or engaged.

And a still further object of my invention is to provide connector bars or members of channel-shape or contour in cross-section, with the con-

volutions of such helically twisted wires permanently secured to the narrower edges or flanges of such channel sections, preferably by a welding operation.

These and other features of my invention are more fully described hereinafter; reference being had to the accompanying drawings, more or less diagrammatic in character, in which:

Figure 1 is a plan view of sufficient of a wire belt of the character to which my invention relates; showing a connector member secured to the convolutions of a helically twisted wire making up the same and serving as a spacing and connecting member to prevent shortening of such wire and in consequence preventing lateral narrowing of the wire fabric or belt with which it is connected.

Fig. 2 is a sectional view taken on the line II—II, Fig. 1.

Fig. 3 is a sectional view on the line III—III, Fig. 1.

Fig. 4 is a plan view of the meeting edges of a pair of sections or panels of the wire fabric, with a connector member disposed between the same and permanently connected to the end wires of the adjoining sections; preferably by welding the convolutions of said wires to opposite sides of the connector member.

Fig. 5 is a sectional view on the line V—V, Fig. 4.

Fig. 6 is a view similar to Fig. 4, showing a similar connector member disposed between sections or panels of the wire fabric made up of helically twisted wires in which the convolutions of the wires of the respective sections or panels are disposed in opposite directions relatively to each other.

Fig. 7 is a sectional view on the line VII—VII, Fig. 6.

Figs. 8, 9, 10, 11, and 12, are sectional views similar to Fig. 7, illustrating connector members of different cross-sectional contour, and

Figs. 13 and 14, are views illustrating modified forms of connector members within the scope of my invention.

Wire belts made of helically twisted wires of the type to which my invention relates are well known articles of manufacture, an early example of the same being shown in the patent of Charles Swinscoe, No. 712,212, dated Oct. 28, 1902.

Heretofore, wire connectors have been employed for connecting the sections or panels of belts of this type and in some instances bar connectors have also been employed, particularly when such sections or panels comprise individual

helically twisted wires having right-hand and left-hand convolutions; one notable example being the structure illustrated in the application of Charles L. Janney, filed August 30, 1929, Serial No. 389,557. In both instances, the helical wires have their free ends twisted together at the margins or sides of the belt, and in the case of connectors or spacers of the Swinscoe type, lateral displacement of the wires—collapse of the convolutions—with consequent narrowing of the fabric, takes place under the traction applied to the belt in pulling or passing it around driving pulleys or other pull-transmitting means.

The principal object of my invention is to permanently secure connector members to the helically twisted wires at various points throughout the length of the belt whereby I am enabled to provide means that will prevent lateral displacement of the wires and avoid the narrowing 20 of the fabric making up the belt.

In Figs. 1, 2 and 3 I have shown a series of helically twisted wires making up a belt of this type; a sufficient number of such wires being shown to indicate their character, and they may be employed in any desired number to form a complete belt of any desired length. For the purpose of preventing lateral displacement of the wires making up such belt, I introduce flat bars therein at intervals throughout the length of 30 the same and weld the convolutions of such wires, or one of them, to such bar. In Figs. 1, 2 and 3, 1, 1, represents the helically twisted wires having convolutions providing the upper and under (or lower) ribs 1^a and 1^b. In this type of belt, the respective ribs extend in the same direction. Within the space between the upper and under (or lower) ribs of certain of these helically twisted wires I introduce a flat bar, such as indicated at 2, which is preferably of a length, crosswise of 40 the belt, the same as the helically twisted wires, and by preference this connector bar occupies the space between the convolutions of the adjacent wires, as clearly indicated in Figs. 1 and 2. This bar is secured in place by welding the convolutions of the adjacent wires thereto, as indicated at 3, or by welding the upper and under (or lower) ribs of the convolutions of the helically twisted wire through which such connector bar passes, as indicated at 3^a. These connector bars may 50 be employed at suitable intervals throughout the length of the belt; being provided in such number as conditions of use of any particular belt may warrant or require. It will be understood that while I have shown this connector bar 2 as associated with helically twisted wires of the character illustrated; that is to say, wires whose upper ribs extend in the direction indicated from upper left to lower right, I may employ connector bars of such type with belts made up of helically twisted wires whose upper ribs extend in what may be termed an opposite direction; that is to say, from upper right to lower left, without departing from my invention. In practice these wires are termed "right" and "left", and the twist of the wires shown in Figs. 1, 2 and 3, is a right-hand twist.

In Figs. 4 and 5 I have shown a connector bar disposed between two sections or panels of wire fabric, in this instance sections of right-hand twisted wires, indicated generally at A. The connector bar 22, shown in Figs. 4 and 5, is of channel-shape or contour in cross-section; comprising a web indicated at a providing a flat surface which will lie in the plane of the upper ribs 1^a of the wire fabric so as to form a substantially plane surface continuous therewith, and edge ribs or

flanges b, which may extend to the plane of the under (or lower) ribs 1^b of the helically twisted wires. The convolutions of the helically twisted wires on opposite sides of this channel-shape connecting member are welded thereto as indicated at 33. 80

In Figs. 6 and 7 I have shown sections or panels of wire fabric made up of helically twisted wires in which the wires 1, of one section or panel, indicated at A'; that illustrated in the drawings as 85 disposed above the connector member, may have their upper ribs 1^a lying in one position; being made of right-hand twisted wires, for instance, while the section or panel of fabric indicated at B' in such view as disposed below the connector member and made up of helically twisted wires 11, have their upper ribs 11^a lying in the opposite direction; being made up of left-hand twisted wires, for instance. In other words, such belt is 90 made of sections or panels of right-hand twisted wires alternated with sections or panels of left-hand twisted wires. These sections or panels may be joined by a connector member 22 of channel section, the same as that illustrated in Figs. 4 and 5, and the convolutions of the respective 100 helically twisted wires of the respective sections or panels may be welded to such connector bar at 33.

In Figs. 8, 9, 10, 11 and 12, I have shown cross-sectional views similar to Fig. 7, illustrating connector members of different cross-sectional contours. 105

Fig. 8 shows a connector member or bar 2^a, of the type illustrated in Figs. 1, 2 and 3.

Fig. 9 shows a connector bar or member 22^a, rectangular in cross-section.

Fig. 10 shows a connector bar or member 22^b, oval in cross-section. 110

Fig. 11 shows a hollow connector member 22^c, which may be oval in cross-section, and Fig. 12, shows a connector bar or member 22^d, substantially hexagonal in cross-section. 115

In all instances the connector members preferably occupy a space equaling the space between the convolutions of the helically twisted wires so that the pitch of the chain, so to speak, 120 is not altered by the presence of the connector members; hence a belt provided with connector members such as I have devised may be passed over toothed driving members, if desired, with the assurance that the teeth of the same will 125 mesh properly with the spaces provided by the openings between adjacent wires making up the fabric of the belt. If, however, this spacing of the wires making up the belt is not essential in the operation of use of the same, the connector members may be of regular contour and equal dimensions in all directions in cross-section; that is to say, square, round, hexagonal, or of other polygonal shape, or the like, as may be desired. And in lieu of hollow connector members of oval 130 contour such as illustrated at 22^c in Fig. 11, I may employ round tubes to the surface of which the convolutions of the helically twisted wire strands may be welded. 135

It is also within the scope of my invention to 140 provide the connector members with flanges or webs projecting from the same and above or beyond the surface of the belt and at any desired curve or angle thereto to serve as conveyer flights. In this connection I have shown in Fig. 145 13 a connector member 22^e having a flange or web 5 which may be integral with the same, and in Fig. 14 I have shown a connector member 22^f having a flange or web 5^a of curved form which may be integral therewith. It will be under- 150

stood, of course, that these webs or flanges may be separate members and attachable to any of the forms of connector members shown.

The art of making belts of these helically twisted wire strands is too well known to require elaborate description. In carrying my invention into effect I may weave sections of the fabric, or in the case of the arrangement shown in Figs. 1, 2 and 3, the fabric may be woven in any lengths, and the connector members applied as desired; being placed within the convolutions of individual wires which may be welded thereto as indicated. The number of these connector members or stretcher bars may be such as the use to which the belt is to be put may require.

In the case of the connector members which are interspaced between sections or panels of the wire fabric, which sections may be made up of wires having their convolutions extending in the same direction, or sections or panels wherein the wires of one have convolutions extending in one direction—right-hand, for instance—and the other section or panel has wires whose convolutions extend in the opposite direction—left-hand, for instance—the end wires of the respective sections are so placed that the convolutions of the same throughout their length abut and touch the sides or edges of such interspaced connector members, and then by means of suitable welding apparatus, electric arc-welding for instance, the touching or abutting portions of such convolutions are welded to the sides or edges of the connector members. And this manner of permanently securing the connector members to the wires of the panels or section of wire fabric making up the belts may be carried out with all forms of connector bars shown. It will be understood, of course, that I am not limited to the forms of connector bars shown, and that any form of bar which may be employed in the manner illustrated and to which the convolutions of the helically twisted wires may be welded or otherwise permanently secured, is within the scope of my invention.

At the same time, other means of securing the helically twisted wires to the connector bars or members may be employed, and it is within the scope of my invention to employ connector members to which single helically twisted or coiled wires are attached at the opposite sides or edges thereof; either pairs of wires with right-hand convolutions, pairs of wires with left-hand convolutions, or a wire with a right-hand convolution on one side or edge of such connector member, and a wire of left-hand convolutions on the opposite side or edge of such connector member, and to apply such connector member to the wire twisting or coiling machine as the wires are being helically coiled or twisted to form the fab-

ric, so that at the required spacings these permanently attached connector members may be associated with the belt fabric made up of the several interlaced helically twisted wires. When so arranged or when arranged in any manner, the ends of the connector members may be permanently attached to the ends of the adjoining wires of the fabric, so that accidental removal of the connector members is impossible. It will be understood, of course, that such end connections may be undone when repairs to the belt are necessary, and that fresh wires may be woven in at any time, as well as fresh connector members applied.

I claim:

1. A connector for woven wire belts made up of sections of helically twisted wires interlaced with each other, comprising a cross-member of channel-shape interposed between pairs of helically twisted wires making up such belt and fixedly secured to each of said wires.

2. A connector for woven wire belts made up of sections of helically twisted wires interlaced with each other, comprising a cross-member of channel-shape interposed between pairs of helically twisted wires making up such belt and welded at its flanged edges to each of said wires.

3. A connector for joining the end wire of a belt section made up of helically twisted wires wound in right-hand convolutions to the end wire of a belt section made up of helically twisted wires wound in left-hand convolutions, comprising a bar fixedly connected to the outer faces of the convolutions of the respective end wires.

4. A connector for joining the end wire of a belt section made up of helically twisted wires wound in right-hand convolutions to the end wire of a belt section made up of helically twisted wires wound in left-hand convolutions, comprising a bar welded to the outer faces of the convolutions of the respective end wires.

5. A connector for joining the end wire of a belt section made up of helically twisted wires wound in right-hand convolutions to the end wire of a belt section made up of helically twisted wires wound in left-hand convolutions, comprising a channel-shaped bar having its edge flanges permanently secured to the outer faces of the convolutions of the respective end wires.

6. A connector for joining the end wire of a belt section made up of helically twisted wires wound in right-hand convolutions to the end wire of a belt section made up of helically twisted wires wound in left-hand convolutions, comprising a channel-shaped bar having its edge flanges welded to the outer faces of the convolutions of the respective end wires.

RAYMOND J. GUBA.
